UNITED STATES PATENT OFFICE

1,985,539

AUTOMATICALLY GOVERNED CONTINUOUS
BURNERWilliam G. Hartwig, Chicago, Ill., assignor to
Railway Utility Company, Chicago, Ill., a cor-
poration of Illinois

Application March 9, 1933, Serial No. 630,112

20 Claims. (Cl. 236—76)

This invention relates to fluid burners adapted to meet a variable heat demand for any use, and particularly burners which usually burn a substantial volume of fuel continuously and have their output regulated automatically, for example, thermostatically, by governing the volume of fuel delivered per unit of time until equilibrium is established between demand and output, and resultant temperature is constant, as distinguished from intermittent burners that have their volume of delivery constant per unit of time and their output regulated by governing the frequency and duration of the periods of extinguishment and reignition, and thereby keeping the resultant temperature within a predetermined range of fluctuation.

One object of the invention is to provide a burner system operating upon the principle stated, in which a single burner, while usually permitted to burn continuously, will be accurately governed in its volume in establishing equilibrium between combustion and heat consumption and in response to variations in the demand; to which end one feature of the invention consists in so combining a fuel delivery element, an adjustable fuel volume governor, a motor for such governor, a heat controlled energy supply for such governor (for example, a thermostatically controlled electric circuit), a commutator imparting to said energy supply a motor actuating phase and a governor locking or holding phase, and a connection through which the motor when actuated, shifts the commutator to its locking phase and thereby controls the adjustment of the governor; the energy supply being preferably subdivided into a plurality of units, each responsive to a different degree within a selected range of temperature and adapted to successively influence the motor and cause a governor adjustment appropriate to the heat output which the energy supply unit represents; and the fuel delivery governor preferably having associated with it additional fluid governing means; for instance, for a combustion supporting medium, that is actuated by the same motor and with an amplitude of movement relatively to the movement of the fuel governor, which is in the same ratio that the two fuel elements should bear to each other in promoting efficient combustion.

Another object of the invention is to provide an embodiment of the invention identified by the operative principle already explained, in which fuel will be entirely cut off from the burner in the event of failure of the motor energy supply, and thereby prevent combustion from continuing un-

controlled; to which end, a feature of the preferred embodiment of the invention resides in continuing the energy supply as a governor-locking influence diverting the energy to a magnetic means for keeping the governor geared to the motor or for otherwise locking or holding the governor; the governor in this instance preferably being moved in one direction only by the motor and having its movement in the other direction imparted by a spring or other constantly acting means which the motor is capable of dominating, when fully energized.

Other objects and identifying principles and illustrative structural embodiments of the instrumentalities for realizing the same will be apparent from the following description.

In the accompanying drawings showing one embodiment of the new system, as well as modifications of some of its elements,

Figure 1 is a side elevational view of a complete electrically actuated valve control unit exclusive of the thermostat, and showing the valves in section;

Figure 2 is a view of the control unit with the connection panel and other parts removed;

Figure 3 is a vertical sectional view of a control unit taken substantially along the line 3—3 of Figure 1;

Figure 4 is a vertical sectional view taken substantially along the line 4—4 of Figure 3;

Figure 5 is a fragmentary vertical section taken substantially along the line 5—5 of Figure 3;

Figure 6 is a plan view partly in section of the structure of Figure 1;

Figure 7 is a fragmentary sectional detail view showing the connection between the air valve and fuel valve control means; and

Figure 8 is a diagrammatic illustration of the circuits used by the control apparatus illustrated in Figures 1 to 7.

Referring to Figures 1 to 4, the numeral 14 represents an electric motor having armature shaft 15 standing in driving relation with a master shaft 24 through reducing gears 16 and 17, the differential gears 18, 19 and 20, and the additional reducing gears 21, 22 and 23. The master shaft 24 acting through instrumentalities described below, imparts movement in the valve opening direction to the gas valve stem 26 and air valve stem 27 in opposition to spring 28 which normally urges said valves in the direction of closing. Also associated with master shaft 24, and partaking of the movements of said shaft, therefore co-ordinated with valve movements, is a commutator 30 carrying an arcuately

5

55

elongated terminal plate 31 and an arcuately narrow terminal 32 having a circumferential extension 33, preferably set below the upper surface of commutator 30. The term commutator 5 is not used so much in a technical sense as with a broad meaning such as would include the structure illustrated or any equivalent device for controlling one or more circuits according to movement.

10 The numerals 34a, 34b, 34c, and 34d represent brushes, each of which is connected, as shown in Figure 8, by independent wiring 36a, 36b, 36c or 36d, with terminals 38a, 38b, 38c and 38d of the circuit closer 39 of the thermostat 40, thus 15 distributing motor energy received through wire 41 from a source, such as a transformer 42. All of these brushes 34a, 34b, 34c and 34d are adapted to contact with either of the terminals 31 or 32. The numeral 44 represents a brush always 20 bearing upon and in a condition to transmit current from the long terminal 31 through wiring 46 to motor 14. When current is delivered, by a falling thermostat, to any one of the brushes 34a, 34b, 34c or 34d, and that brush is resting 25 upon terminal 31, the current is supplied to motor 14 enabling it to overcome the valve spring 28 and open the valves. But this movement of the valves is imparted also to the commutator 30, so that by the time a predetermined opening 30 adjustment has taken place in the valves, the commutator has moved to the left in Figure 8 sufficiently to shift the brush in question over upon the narrow terminal 32, whereupon the motor energizing current is cut off by the passage 35 of terminal 31 from under the brush. Contact 32, through its extension 33 contacting brush 47, completes a holding circuit 48 hereinafter to be described, to lock the motor and valves at the new adjustment. When the thermostat reacts 40 from the resultant increase of fuel delivery, it opens such holding circuit 48, thereby permitting the valves to move in the closing direction, and causing the commutator to move to the right until some commutator brush, lying to the right 45 of the narrow or resistance terminal 32 and up to this time out of contact therewith but having its circuit still closed at the thermostat, comes upon the narrow terminal 32 and again completes the holding circuit 48 to hold the valves at a new 50 metering position.

In describing the operating of the holding circuit, it is necessary to explain the operation of the differential ratchet mechanism. Included in the holding circuit 48 is an electromagnet 55 coil 49. In series with the wiring 46 is another electromagnet coil 50. The functions of the coils 49 and 50, which will be explained later, are similar. The coil 49, however, is a high resistance coil, since the current therethrough is 60 not externally restricted, while the coil 50 is a comparatively low resistance coil since this coil is in series with the motor. These coils control the differential ratchet mechanism.

This differential ratchet mechanism and its 65 operation are best seen in Figures 3 and 4. The gears 17 and 18 are rigidly connected to operate in unison, as are the gears 20 and 21. The bevel gear 19 is freely rotatable on the planetary ring 52. This ring is rotatably mounted on the shaft 70 54 which also furnishes the common support for gears 17, 18, 20 and 21. If the planetary ring 52 is restricted from rotation, then the bevel gears 18 and 20 are geared together through the bevel gear 19. Under this condition power may 75 be transmitted from the motor 14 through gear

17 and bevel gear 18 to the bevel gear 19 and from it to the bevel gear 20 and through the reducing gears 21, 22 and 23 to the master shaft 24. Likewise if the planetary ring continues to be held from rotation then the master shaft 5 24 cannot be rotated backwards under the influence of valve spring 28 without turning the motor backwards, since the same gearing remains operative. However, the various reduction gears are of such high ratio that the force 10 of the spring would be unable to overcome the friction of such gears and the friction and inertia of the rotor of the motor 14. As an added safeguard, however, the spring friction brake 56 is preferably provided which bears on the face 15 of gear 18. If now the planetary ring 52 is released, the friction and inertia beyond that point is avoided, and the strength of the spring 28 is sufficient to close the valves, thereby 20 rotating the master shaft 24, the reduction gears 21, 22 and 23 and the planetary ring 52, but not rotating the bevel gear 18.

From the above it is seen that the control of the valves rests in the planetary ring 52. This ring has on its periphery a series of ratchets which 25 face in a direction to oppose the rotation of the planetary ring 52 when engaged by a pawl. Two pawls are provided, one numbered 60 and the other 61. These pawls are normally urged to a disengaged position by a spring. The pawl 60 30 may be closed by the coil 49 in the holding circuit 48, and the pawl 61 may be closed by the coil 50 in the motor circuit 46. Except for their time of operation, the immediate effects of the pawls are identical, and in fact, if preferred, a single pawl 35 may be used, controlled by both the coils 49 and 50, in which case the coils 49 and 50 may be mounted on a single armature if desired. Each pawl when energized by its magnet prevents the rotation of the planetary ring 52 and makes the 40 gearing operative. When one of the brushes in contact with terminal 31 is supplied with current through the thermostat, circuit 46 is completed, thereby energizing both the motor 14 and the coil 50. The coil 50 operates pawl 61 to lock the 45 planetary ring so that as the motor 14 turns it rotates the various gears and opens the valves. This movement continues until the terminal 31 passes from under such brush. Such brush then contacts the terminal 32 and through it the circuit 50 48 energizes coil 49, which, by means of the pawl 60 continues the locking of the planetary ring 52 thereby preventing the closing of the valves. When the thermostat interrupts the locking circuit through the terminal 32, the coil 49 is de- 55 energized and the pawl 60 is shifted by the spring 62 to release the planetary ring 52, thereby releasing the valves and permitting them to close.

Provision may be made for subjecting the motor energizing circuit to the control of a thermostatic element in the path of a fluid that is dependent upon the burner for its heat, by extending the return or grounding wire 64 (see Figure 8) of motor 14 through a suitable path; for instance, connector 65 and wires 66, to a thermostat 67 of any circuit controlling type adaptable to a fluid conduit. The wires 66 may be extended by the wires 68 to permit introduction of a pilot-light control of conventional type, for 60 instance, a tipping mercury switch 69 responding to a bimetallic distortion member within heat-absorbing relation to the pilot light. From the wires 68 of this pilot control, the circuit may be traced through wire 71 to transformer 42, which 65 70 75 78 80 85 90 95 98

is the energy source for motor 14, as already explained. An indicator light 72 may also be connected to the transformer 42 through the mercury switch 69, its wires 68 and the wires 73, to indicate when the pilot light is burning.

While various constructions of coordinated fuel and air valves may be used under control of the system above described, the preferred construction is illustrated best in Figure 5, with some reference also to Figures 1, 3, 4, 6 and 7. In this construction fuel valve stem 26, urged toward closing by coil spring 28, is connected to hook member 74 which engages eccentric roller 76 on disk 77, which is fixed on shaft 78. To the other end of shaft 78 is keyed crank lever 80, which is provided with a slot 81 positioned to receive a crank pin 82 mounted eccentrically on gear 23, which may be turned by the motor as previously described. Secured to crank lever 80 is a gear segment 84 which meshes with a complementary gear segment 85 keyed to a counter-shaft 86. Also mounted on counter-shaft 86 is an arm 87 to which is pivoted the air valve stem 27 secured to air valve 88. It is thus seen that through the gear segments the air and fuel valves are operated in unison, both being opened by crank pin 82 and closing as said crank pin yields under the pressure of valve spring 28.

It is desirable, however, to have some convenient means of adjusting the air valve relatively to the fuel valves. For this reason the arm 87 is not keyed to the shaft 86, but is rotated by means of the arm 90 which is keyed to said shaft 86, and the adjustment screw 91 which is carried by the arm 90 and bears against the arm 87. The arm 87 is held against the screw 91 by the spring 92, which therefore is the air valve closing spring. Additional adjustment may be made by adjustment of the valve stem 26, but this stem often is not conveniently accessible.

On rare occasions it may be desirable to adjust the valves by hand, for which purpose the manual shift lever 94 is provided, which may be formed as an extension of the crank arm 80. Means for locking this manual shift lever in a variety of positions should be provided, but it is preferred that the use of an auxiliary key 96 or other special means be required for this purpose.

As an additional convenience, adjustment of the commutator disk 30 with respect to the valves may be accomplished by the screws 97 (Figure 1).

The numeral 98 represents the fuel valve proper, guided by spider 99 in its movement relatively to tapered nozzle seat 100; and 88 represents the air valve proper moving relatively to its seat or ring 102 in flange coupling 103. An important feature of this valve design resides in the condition that the valves are closely related to the mixing point, so that fuel arrives at the escape opening under full pressure and there is no open space for residual gas to accumulate in forward of the valve.

It is to be understood that many other embodiments of the invention, including some in improved form, will be apparent, and in the course of time more will be devised by those skilled in the art. It is not desired that this invention be limited to the details described, for its scope includes all such forms or improvements as come within the spirit of the following claims construed as broadly as the prior art will permit.

What is claimed is:

1. In an electrical control for combustion systems of the type employing a fluid metering ele-

ment biased to a given position and operable in one direction from said position by a motor, a commutator adapted to supply current to the motor of such system, having a motor energizing terminal, a motor energizing circuit having and controlled by brush means contacting with and separating from said terminal under relative movement set up between the commutator and said brush means, and means whereby said relative movement between the brush means and the commutator is caused to take place in definite relation to movement of the fluid metering element.

2. In an electrical control for combustion systems of the type employing a motor actuated fluid metering element, a commutator adapted to supply current to the motor of such system, having a motor energizing terminal, a motor controlling circuit having brush means contacting with and separating from said terminal under relative movement set up between the commutator and said brush means, and means whereby said relative movement between the brush means and the commutator is caused to take place in definite relation to movement of the fluid metering element; said commutator also having a terminal adapted to cause locking of the metering element and upon which terminal the brush means moves upon leaving the motor energizing terminal.

3. An electrical control as described in claim 1, in which the brush means includes a plurality of brushes spaced from one another along the path of the commutator, each of which brushes, when individually energized, is adapted to supply current through the energizing terminal to the motor, and means to hold the metering element made effective by an energized brush upon moving off of said terminal.

4. An electrical control as described in claim 2, in which said brush means comprises a plurality of separately fed brushes adapted to move successively from the motor energizing terminal to the holding circuit terminal and thereby impart to the motor a series of limited adjusting movements.

5. In a combustion system, a duct adapted to supply a combustion supporting fluid, means governing the delivery of fluid through said duct, adjustable to different positions for metering the fluid supply, a motor adapted to impart movements of adjustment to said governing means, a plurality of motor energizing circuits adapted to be individually energized and interrupted for developing controlled periods of movement in the motor, a commutator having a motor energizing terminal and a holding circuit terminal, and a contact brush for the respective motor energizing circuits, each of which brushes in response to relative movement between the commutator and the brush is caused to pass from the motor energizing terminal to the holding circuit terminal.

6. A combustion system as described in claim 5, in which the holding circuit terminal is of restricted dimension which causes each brush to separate therefrom and establish control in succeeding brushes shifting from the motor energizing terminal to said holding circuit terminal.

7. A combustion system as described in claim 5, in which the holding circuit terminal being of restricted dimension causes each brush to separate therefrom and establish control in succeeding brushes shifting from the motor energizing terminal to said holding circuit terminal, and

- the several brushes being caused to move successively onto the holding circuit terminal and thence to the motor energizing terminal under reverse relative movement between the commutator and 5 the brushes.
8. In a combustion system, a duct for supplying a combustion supporting fluid, a governor adjustable to meter the fluid supplied through said duct, means constantly influencing the 10 governor in the direction to decrease the flow of fluid, a motor adapted to influence said governor in the direction to increase the flow of fluid and adapted to dominate the said means constantly influencing the governor first named, a commutator having electrical connections through which it is adapted to energize said motor and also to deenergize the same and having connections through which it is moved from energizing to deenergizing position by the movement of the 15 motor in response to energizing current supplied by the commutator, and a thermostatic means controlling the supply of current to said commutator.
9. A combustion system as described in claim 8, 20 in which the deenergizing position of the commutator supplies current to a holding circuit to hold the governor in its then position.
10. In a combustion system, the combination with means for supplying fuel and air of valve 25 means for controlling said means, a common driving mechanism for said valve means imparting thereto movements which proportion air and fuel delivered appropriately to support combustion, an electric motor having connections 30 through which it drives said actuating mechanism in a direction that causes opening of the valve means, means normally urging said valve means in the direction of closing, a commutator having connections through which it supplies 35 electrical energy to said motor, said commutator having a motor energizing terminal and a holding circuit terminal, a series of brushes, all of which 40 coact with the commutator, driving connections through which movement of the motor is transmitted to the commutator, the brushes by movement so transmitted, passing successively from the motor energizing terminal to the holding circuit terminal, individual circuits for the respective 45 brushes, and a thermostat having separate 50 circuit closers for the respective brush circuits and adapted to operate the latter successively under changes in surrounding temperature.
11. In a combustion system, a duct for supplying a combustion supporting fluid, a governor 55 adjustable to meter the fluid supplied through said duct, means constantly influencing the governor in the direction to decrease the flow of fluid, a motor adapted to influence said governor in the direction to increase the flow of fluid and 60 adapted to dominate the said means constantly influencing the governor, a commutator having electrical connections through which it is adapted to energize said motor and also to deenergize the same and having connections through which it is 65 moved from energizing to deenergizing position by the movement of the motor in response to energizing current supplied by the commutator, and a thermostatic means controlling the supply 70 of current to said commutator; said motor and associated parts having sufficient friction to reliably resist the means constantly influencing the 75 governor when the connections through which the governor is moved by the motor are maintained in their effective condition even through the motor is deenergized.
12. In a combustion system as characterized by claim 11, a holding terminal on said commutator, and means effective when said motor is energized or when said holding terminal is energized for maintaining effective the connections through which the governor is moved.
13. A combustion system, a valve for modulating the fuel, a motor for moving said valve, a commutator movable jointly with said valve, a motor energizing terminal and a holding terminal 10 adjacent to one another on said commutator, a plurality of spaced brushes arranged to engage the motor energizing terminal and to sequentially move from said motor energizing terminal to said holding terminal and from said holding terminal 15 as the valve moves in an opening direction, a thermostat having a plurality of successively closed contacts each connected with one of the brushes, a circuit through said motor and said motor energizing terminal and any of said brushes 20 with its corresponding thermostat contact for causing said motor to move in a valve opening direction, bias means constantly urging said valve in a closing direction, and locking means controlled by a circuit through said holding 25 terminal for preventing said bias means from being effective when an energized brush contacts said holding terminal.
14. The structure of claim 13 in which the locking means comprises means for rendering effective the connections between said valve and said motor whereby the friction of said motor and its associated parts is used to resist said bias means.
15. The structure of claim 13 in which the locking means comprises means for rendering effective the connections between said valve and said motor whereby the friction of said motor and its associated parts is used to resist said bias means; and additional means for rendering said connections effective when said motor is energized.
16. The structure of claim 13 in which the locking means comprises a planetary gear ring in a train of gears in the connections between said valve and said motor, latch means for locking said ring to make said train of gears effective, and magnetic means for operating said latch means.
17. The structure of claim 13 in which the locking means comprises a planetary gear ring in a train of gears in the connections between said valve and said motor, latch means for locking said ring to make said train of gears effective, and separate magnetic coils respectively controlled by said motor energizing and holding terminals for operating said latch means.
18. In an electrical control for combustion systems of the type employing a fluid metering element biased to a given position and operable in one direction from said position by a motor, a commutator adapted to supply current to the motor of such system, having a motor energizing terminal, a motor energizing circuit connected with said terminal, contact means controlling said circuit by contacting with and separating from said terminal upon relative movement of said commutator, and means whereby said relative movement of the commutator is caused to take place in definite relation to the movement of the fluid metering element.
19. In an electrical control for combustion systems of the type employing a fluid metering element biased to a given position and operable in one direction from said position by a motor, a commutator adapted to supply current to the mo-

tor of such system, having a motor energizing terminal, a motor energizing circuit connecting said terminal with said motor, a plurality of brushes contacting said terminal in its initial 5 position, each of which when individually energized is adapted to supply current through said terminal to said motor, means for causing a relative movement between the brush means and the commutator in definite relation to the movement 10 of the fluid metering element, said movement successively separating the said brushes from said terminal, and means made effective by the successive brushes as they leave said terminal for preventing a return of the metering 15 element toward its biased position.

20. A combustion system, a valve for modulating the fuel and biased to a relatively closed position, a motor for opening said valve, a train of gears connecting said motor and said valve, and including a planetary gear ring requiring to be locked to render said gears effective, latch means for locking said ring, commutator means for energizing said motor and simultaneously causing the operation of said latch means and at other times causing the operation of said latch means without energizing said motor; said motor and associated parts having enough friction to prevent the closing of said valve when said latch means is operated.

WILLIAM G. HARTWIG. 15
